PULP INSULATING MACHINE

Waldemar C. Ewaldson, Millington, and John N. Selvig, Westfield, N. J., assignors to Western Electric Company, Incorporated, New York, N. Y., a corporation of New York

Application April 16, 1947, Serial No. 741,922

6 Claims. (Cl. 92—55)

1

This invention relates to pulp insulating machines, and more particularly to machines for forming insulating coverings of pulpous material on electrical conductors.

In insulating machines for forming insulating coverings of pulpous material on electrical conductors while they advance longitudinally through the machine, the material is fed continuously to a Fourdrinier wire of the continuous type while the upper portion of the wire, which receives the material, travels in a plane parallel with a plane through which the electrical conductors are advanced. A suction box is positioned beneath the upper portion of the wire to draw the major portion of the liquid or water from the material leaving a covering on the conductors. To facilitate in the formation of individual ribbons of the material on the individual conductors, deckles, providing individual channels for the conductors and for the material from which the individual ribbons are formed, are positioned above the upper portion of the wire leading away from the entrance end thereof where the material is initially applied to the wire.

An object of the invention is to provide a member, in pulp insulating machines for insulating electrical conductors, which embodies a press roll adjustable axially relative to the plane through which the conductors travel and vertically relative to this plane to control the formation of the pulpous material about the conductor.

A further object of the invention is to provide a tiltable frame to support the press roll as well as the deckles relative to the plane of the conductors between an operating position and a loading position.

With these and other objects in view, the invention is embodied in a pulp insulating machine including a Fourdrinier wire of the continuous type driven on supporting rollers to cause an upper portion thereof to travel in a given direction with electrical conductors to be covered with pulpous material fed to the wire and relative to a suction box positioned beneath the upper portion of the wire to draw water from the material as it travels with the wire and the conductors. Within this structure, the invention comprises a frame supported above the upper portion of the wire for a shaft which rotatably supports a press roll positioned adjacent the exit end of the upper portion of the wire. The shaft has elements mounted thereon, carried by the frame and movable therein to vary the position of the press roll relative to the upper portion of the wire to press excess water from the material covering the con-

2

ductors. The elements mounted on the shaft of the press roll are circular in cross-section and are disposed in aligned circular openings of the frame, the elements being mounted eccentrically on their spaced portions of the shaft whereby rocking of the shaft with the elements in the apertures of the frame will move the press roll toward or away from the wire to vary the distance between the roll and the wire, thus varying 10 the space through which the pulp covered conductors will travel.

The frame supporting the press roll also supports spaced parallel deckles providing channels for the individual electrical conductors and their 15 supplies of material. The frame is pivotally supported and through an operating mechanism it may be tilted from its operating position adjacent the wire and conductors to a loading position spaced from the wire and the conductors.

Other objects and advantages will be apparent from the following detailed description when considered in conjunction with the accompanying drawings, wherein

Fig. 1 is a fragmentary side elevational view of 25 a pulp insulating machine embodying the invention;

Fig. 2 is an enlarged fragmentary sectional view taken along the line 2—2 of Fig. 1;

Fig. 3 is an enlarged fragmentary sectional view 30 taken along the line 3—3 of Fig. 1;

Fig. 4 is an end elevation view of the structure shown in Fig. 3 looking from the right;

Fig. 5 is an enlarged end elevation view of the structure shown in Fig. 3 looking from the left, 35 portions thereof being shown in section; and

Fig. 6 is a top plan view of the structure shown in Fig. 5.

Referring now to the drawings, the apparatus in which this invention is a part is a pulp insulating machine only a small portion of which is shown in Figs. 1 to 3, inclusive. The portion of the machine shown in these figures includes a Fourdrinier wire 10 which is of the continuous type supported by spaced rollers at each end of a suction box 11, the rollers not being shown in the drawings. One or more of the supporting rollers may be driven to drive the wire continuously at a given speed to cause the upper portion of the wire which is shown in drawings to travel at a given speed in the direction of the arrow with a plurality of electrical conductors 12 which are to receive coverings of pulpous material 14 fed to the upper portion of the wire 10. A cover 15 of the suction box 11 is perforated at 16 at spaced positions 50 throughout its length and width whereby the ma-

major portion of the water in the material surrounding the electrical conductors 12 may be withdrawn from the material during advancement of the wire with the conductors and material. The electrical conductors are guided by individual sheaves 17 to like positions adjacent the wire 10 beyond the line of application of the material to the wire. When the conductors leave their sheaves 17 they travel in a given plane with the wire, their advancement longitudinally being 10 caused by a takeup mechanism (not shown).

The invention incorporated in the pulp machine includes a press roll 20 supported by a tiltable frame 21 which carries spaced deckles 22 to provide channels for the pulpos material applied to each electrical conductor. The frame 21 is pivotally supported at 25, the shaft serving as a pivot for the frame being journaled in suitable bearings 26 of the main frame 27 of the machine. Adjustable screws 29 extending through internally threaded lugs 30 disposed in spaced positions (Fig. 1) on the front of the frame rest upon the cover 15 of the suction box 11 to adjustably locate the position of the frame, particularly the positions of the deckles 22 and a press roll 20 relative to the wire 10.

The deckles 22 are formed of metal strips having their upper ends disposed in notches of mounting strips 32 and secured in place by wires or rods 33 extending through aligned apertures formed in the mounting strips and the deckles. In the present embodiment there are three mounting strips 32, removably secured to brackets 34 by the aid of screws 35, the brackets 34 being fixedly mounted upon lateral portions 36 of the frame. The spaces 38 between the bars or deckles 22 form channels for the pulpos material 14 for each electrical conductor 12, these channels being reduced in width adjacent the wire 10, by inwardly projecting portions 39 of the deckles 22.

The frame 21 may be tilted from the operating position shown in the drawings to a loading position away from the wire 10 and the conductors, which is desirable for loading the machine, that is, for conditioning the machine for operation, and the threading of the electrical conductors therethrough. The tilting mechanism is shown mainly in Figs. 1 and 2 and includes a threaded rod 40, the upper end of which is connected to a lateral member 41 supported in a socket 42 in the outer end of a bracket 43 fixed to the central portion of the back wall 44 of the frame 21. A nut 46 is disposed on the threaded rod 40 and is supported for rotation in a bearing 47, but held against longitudinal movement in a housing 48. A beveled gear 49 is fixedly mounted on the nut 46 and interengages a beveled gear 50 pinned to a shaft 51 which supports a hand wheel 52. The shaft 51 is journaled in a bearing 53 of the housing 48 while the housing 48 is supported by a pivot 54 carried by the main frame 27. Rotation of the hand wheel will cause rotation of the gears 50 and 49 to rotate the nut 46 causing the threaded rod 40 to move downwardly to tilt the frame 21 about its pivot 25.

The press roll 20 is mounted on the frame adjacent the exit end of the suction box 11, its main purpose being to force the major portion of the water, remaining in the pulpos material after it passes over the apertures 16 and cover 15 of the suction box on the wire 10, from the material. The outer portion 55 of the roll 20 is formed of a resilient material such as rubber

and has equally spaced annular grooves 55' in its periphery with like smooth surfaces 56 therebetween. The roller 20 is rotatably supported on a shaft 58 in a suitable manner (not shown) the shaft being held against rotation normally. Eccentric elements 59 and 60 are mounted near the ends of the shaft 58. These eccentric elements have circular outer surfaces 61 and 62 of like diameters which are disposed in aligned supporting apertures 63 and 64. The aperture 63 is in a bracket 65 which is mounted on the frame 21. The aperture 64 is in an adjusting member 66 which is in the form of a sleeve disposed concentric with the element 60. Apertures 67 and 68 of the elements 59 and 60 in which the shaft 58 is disposed are in axial alignment with each other, but eccentric with respect to the general centerline or axes of the elements 59 and 60 and their supporting apertures 63 and 64.

A collar 70 is mounted on one end of the shaft 58 adjacent the element 59 and carries an arm 71 for use in rotating the collar and with it the shaft 58 and elements 59 and 60 to cause adjustment of the roll vertically relative to the wire 10. A pin 72 carried by the bracket 65 is positioned to be engaged by the arm 71 to limit its movement in one direction, and adjustable stop screw 73 carried by threaded lug 74 on the bracket 65 is positioned to be engaged by the arm 71 and limit its movement in the opposite direction.

The sleeve 66 is held in a given position on the eccentric element 60 by pairs of lock nuts 78 mounted upon the threaded ends of the element 60. A bracket 80 mounted on the frame 21 is apertured at 81 to receive the sleeve 66 and permit longitudinal movement of the sleeve in the aperture. A cam-like slot 82 (Figs. 3, 5 and 6) is formed in the upper portion of the bracket 80 to receive an actuating arm 84 which extends through the slot 82 and has its threaded end 85 disposed in a threaded aperture 86 of the sleeve 66. Recesses 88 and 89 are formed in the bracket 80 at the extremities of the slot 82 to receive the inner end of a handle 90 disposed concentric with the arm 84 and normally urged inwardly toward the sleeve by a spring 91 which is housed in the handle concentric with the arm 84. The recesses receive the inner end of the handle 90 to lock the arm in either position depending upon the desired adjustment of the press roll laterally of the wire 10 to position either the grooves 55' or the intermediate flat surfaces 56 in engagement with the electrical conductors 12.

During the operation of the pulp insulating machine, a given number of electrical conductors are advanced continuously beneath their sheaves 17 and then in a given plane adjacent the upper portion of the Fourdrinier wire 10 to which pulpos material 14 is applied in advance of the conductors. With the frame 21 in its operating position, the initial supply of material is divided into the channels 38, formed to receive the conductors by the deckles 22, thus controlling the material for each conductor as it moves on the wire therewith. During the movement of the wire with the conductors and the individual supplies of material in the channels, water in the material is drawn therefrom through the apertures 16 in the cover 15 of the suction box 11 eventually forming what appears to be paper ribbons surrounding each electrical conductor. It is not possible for the suction box to withdraw

all the water desired from the material before leaving this area and for this reason the press roll is added to force additional water from the pulp and compress the ribbon-like material about each conductor.

The conductors 12 may vary in size. Although during one operation of the machine, conductors of only one size are fed through the machine to receive their insulating covering, the machine may be adjusted later to insulate other groups of wires of different sizes. These variations require at least vertical adjustment of the press roll, to vary its position relative to the wire with variations in the sizes of the conductors, and longitudinal adjustment of the roll whereby the flat surfaces 56 will engage the tape covered conductors of smaller sizes while the grooves 55' may be positioned to engage the tape covered conductors of larger sizes. To adjust the press roll vertically the arm 71 (Fig. 4) is moved into engagement with either stop 72 or 73 or to any desired position therebetween. This movement of the arm 71 causes rocking movement of the shaft 58 with its eccentric elements in the aligned apertures supporting them, varying the position of the press roll relative to the wire 10.

Longitudinal adjustment of the press roll from the solid line position shown in Figs. 3, 5 and 6 to the broken line position shown in Fig. 3 may be accomplished by moving the handle 90 outwardly against the force of its spring 91 (Fig. 5) until it is free of the recess 88 then moving the arm 84 with the handle 90 until the handle is received in the recess 89. This movement of the arm 84 in the slot 82, which acts as a cam, will cause the sleeve 66 to move axially to the left a given distance moving with it the eccentric elements 60 and 59, the shaft 58 and the press roll 20 so that the press roll will be moved approximately one-half the distance between each annular groove 55'. In this manner, if the annular groove 55' were positioned adjacent the paths of the electrical conductors, they will at this time be positioned between the paths of the conductors causing the intermediate smooth surfaces 56 to ride upon the covered conductors.

When it is desirable to mend a broken conductor, to replace any of the parts including the wire or to thread new conductors through the machine, the working area may be made accessible by rotation of the hand wheel 52 (Fig. 2) to tilt the frame into its loading position away from the wire.

Although specific improvements of the invention have been shown and described, it will be understood that they are but illustrative and that various modifications may be made therein without departing from the scope and spirit of this invention as defined by the appended claims.

What is claimed is:

1. In a pulp insulating machine including a Fourdrinier wire of the continuous type driven on supporting rollers to cause an upper portion thereof to travel in the same direction as electrical conductors are advanced longitudinally in close proximity to the wire whereby the conductors may be covered with pulp fed to the wire prior to the said upper portion of the wire traveling over a suction box positioned beneath the upper portion of the wire to draw water from the pulp as it travels with the wire about the conductors, a tiltable frame supported above the upper portion of the wire and having an operating position adjacent the wire and a loading position away from the wire, deckles supported at

parallel spaced positions by the frame between the conductors to divide the pulp into ribbons for the conductors after the pulp is fed to the wire when the frame is in its operating position,

5 a pivotal support for the frame, a threaded rod having one end connected to the frame, a nut threadedly mounted on the rod, a pivotal support for the nut, and means to rotatably drive the nut on the rod to move the rod longitudinally to move the frame between its operating and loading positions.

2. In a pulp insulating machine including a Fourdrinier wire of the continuous type driven on supporting rollers to cause an upper portion thereof to travel in the same direction as electrical conductors are advanced longitudinally in close proximity to the wire whereby the conductors may be covered with pulp fed to the wire prior to the said upper portion of the wire traveling over a suction box positioned beneath the upper portion of the wire to draw water from the pulp as it travels with the wire about the conductors, a tiltable frame supported above the upper portion of the wire and having an operating position adjacent the wire and a loading position away from the wire, deckles supported at parallel spaced positions by the frame between the conductors to divide the pulp into ribbons for the conductors after the pulp is fed to the wire when the frame is in its operating position, a pivotal support for the frame, a threaded rod having one end connected to the frame, a nut threadedly mounted on the rod, a pivotal support for the nut, and means to rotatably drive the nut on the rod to move the rod longitudinally to move the frame between its operating and loading positions.

3. In a pulp insulating machine including a Fourdrinier wire of the continuous type driven on supporting rollers to cause an upper portion thereof to travel in the same direction as electrical conductors are advanced longitudinally in close proximity to the wire whereby the conductors may be covered with pulp fed to the wire prior to the said upper portion of the wire traveling over a suction box positioned beneath the upper portion of the wire to draw water from the pulp as it travels with the wire about the conductors, a frame supported above the upper portion of the wire and having aligned apertures in opposing sides thereof, a press roll positioned adjacent the exit end of the upper portion of

45 the wire, a shaft to rotatably support the press roll extending therethrough and through the aligned apertures in the frame, eccentric elements mounted on the portions of the shaft in the apertures to cooperate with the frame to 50 support the shaft and press roll with their axes coincident with each other and parallel with the axes of the eccentric elements, whereby 55 rocking movement of the shaft with the eccentric elements in the apertures will vary the position of the press roll relative to the wire and maintain the axis of the roll parallel with the wire, means for rocking the shaft with the eccentric elements, and means to control the rocking movement of the shaft and eccentric elements to control the position of the press roll

60 relative to the wire.

4. In a pulp insulating machine including a Fourdrinier wire of the continuous type driven on supporting rollers to cause an upper portion thereof to travel in the same direction as elec-

trical conductors are advanced longitudinally in close proximity to the wire whereby the conductors may be covered with pulp fed to the wire prior to the said upper portion of the wire traveling over a suction box positioned beneath the upper portion of the wire to draw water from the pulp as it travels with the wire about the conductors, a frame supported above the upper portion of the wire and having aligned apertures in opposing sides thereof, a press roll positioned adjacent the exit end of the upper portion of the wire, a shaft to rotatably support the press roll extending therethrough and through the aligned apertures in the frame, eccentric elements mounted on the portions of the shaft in the apertures to cooperate with the frame to support the shaft and press roll with their axes coincident with each other and parallel with the axes of the eccentric elements, whereby rocking movement of the shaft with the eccentric elements in the apertures will vary the position of the press roll relative to the wire and maintain the axis of the roll parallel with the wire, means for rocking the shaft with the eccentric elements, a pivotal support for the frame, and mechanism operable to move the frame with the press roll about the said pivot between an operating position adjacent the wire and a loading position spaced from the wire and conductors.

5. In a pulp insulating machine including a Fourdrinier wire of the continuous type driven on supporting rollers to cause an upper portion thereof to travel in the same direction as electrical conductors are advanced longitudinally in close proximity to the wire whereby the conductors may be covered with pulp fed to the wire prior to the said upper portion of the wire traveling over a suction box positioned beneath the upper portion of the wire to draw water from the pulp as it travels with the wire about the conductors, a frame supported above the upper portion of the wire, a press roll positioned adjacent the exit end of the wire and having spaced annular grooves in its periphery with intermediate smooth portions, a shaft to rotatably support the press roll, means carried by the frame to support the shaft for longitudinal movement, and cam operable means to move the shaft longitudinally to shift the press roll laterally of the wire and conductors to selectively position the grooves or the smooth portions of the press roll adjacent the paths of the conductors.

6. In a pulp insulating machine including a Fourdrinier wire of the continuous type driven on supporting rollers to cause an upper portion thereof to travel in the same direction as electrical conductors are advanced longitudinally in close proximity to the wire whereby the conductors may be covered with pulp fed to the wire prior to the said upper portion of the wire traveling over a suction box positioned beneath the

5 upper portion of the wire to draw water from the pulp as it travels with the wire about the conductors, a frame supported above the upper portion of the wire, a press roll positioned adjacent the exit end of the wire and having spaced annular grooves in its periphery with intermediate smooth portions, a shaft to rotatably support the press roll, means carried by the frame to support the shaft for longitudinal movement, cam operable means to move the shaft longitudinally to shift the press roll laterally of the wire and conductors to selectively position the grooves or the smooth portions of the press roll adjacent the paths of the conductors, and means to lock the shaft with the press roll in either position.
